CATCH MECHANISM

Carl R. Hennicke, Cleveland, Ohio, assignor to
Eberhard Manufacturing Company, Division of
the Eastern Malleable Iron Company, Cleve-
land, Ohio, a corporation of Connecticut

Application September 12, 1936, Serial No. 100,472

1 Claim. (Cl. 70—196)

This invention relates to catch mechanism for securing a movable member, and more particularly, is an improvement over the catch mechanism disclosed in application Ser. No. 29,501, filed 5 July 22, 1935, for securing in locked position the actuating member for latch mechanism for a refrigerator truck or car.

An object of the present invention is to so arrange the construction and relative positioning 10 of the parts of this mechanism as to prevent an unauthorized person picking the lock.

In the accompanying drawing, which illustrates my invention:

Figure 1 shows in elevation a portion of the 15 latch mechanism which is described in detail and claimed in the application above referred to;

Figure 2 is a plan view of the actuating member or lever, a portion of the closure being shown in section;

Figure 3 is a view in elevation similar to Figure 1, but on an enlarged scale, part of the housing for the hook elements being broken away on the line III—III of Figure 4;

Figure 4 is a vertical transverse section on the 20 line IV—IV of Figure 2.

As described more in detail in the above referred to application, a closure member 5 is forced into place within a frame 6 by bolts (not shown) actuated by linkages 7 and 8, pivotally 25 connected to racks 9 and 10. The racks 9 and 10 mesh with the gear teeth of an actuating gear 11, within a casing 12. The shaft 14 on which the gear 11 is mounted is provided with a squared shank engaged within a corresponding opening 30 in the gear 11; and an actuating member or lever 15 is fixed on the shaft 14 on the outside of the closure 5 for rotating the gear and accordingly 35 operating the latch mechanism. Catch mechanism is provided at the locking position of the handle or lever 15. This catch mechanism constitutes the invention in the present application. It is obvious that this mechanism is suitable for 40 securing movable members of other descriptions than the one illustrated and above described.

The invention is more particularly applicable to 45 securing an elongated member in position, but the advantages of the catch mechanism do not depend upon pivotal movement of this movable member.

As illustrated more particularly in Figures 3 and 4, a housing 16 is secured to the frame 6. A chamber 17 having an extension 18 through the front of the housing receives a cylinder lock 20. A diaphragm 21 extends across the interior 50 of the housing, part way up, as shown more

particularly in Figure 3. A plate 22 (see Figure 4) is recessed into the housing at its back, and is held against the housing by screws 23, threaded into the rear of the cylinder lock 20.

In addition to holding the cylinder lock in 5 position, this plate has the further function of providing the rear bearing for a shaft 25. This shaft is formed with a shoulder for engaging the plate 22 which prevents the shaft from backing out. The forward end of the shaft 25 is 10 milled down to a tongue 26 (see Figure 3) which serves the double purpose of engaging the cylinder of the lock 20 and also as a means for actuating a pawl 27 which is in this way caused to rotate with the shaft 25. The hook element itself 28 15 is rotatably mounted on the shaft 25 between the diaphragm 21 and the plate 22, being free to swing without turning the shaft. It is, of course, apparent that with this construction, the catch mechanism can be reversely mounted so as to 20 swing either clockwise or counterclockwise depending upon the positioning of the hook element. A light spring 29 biases the hook element 28 toward 25 operative position, i. e., in a clockwise direction as viewed in Figure 3. As is apparent from 25 that figure, one end of the spring is caught about one of the screws 23 and the other end presses against a screw 30 or other similar lug or abutment on the hook element 28.

A second hook element 32 is riveted into and 30 made a part of the handle or lever 15. The rivets 33 or other suitable attachment devices whereby the hook element 32 is secured in the handle 15, are hidden behind a portion 34 of the housing 16 which serves as a guard. This guard is cut 35 away on its inner lip at 35 to urge the lever 15 into position as it is lowered, and furthermore covers the rivets 33 so as to prevent their removal with consequent destruction of the security of 40 the catch mechanism.

The projecting hook element 32 is formed with a deep shoulder 36 on its open side; and as a result, the portion of the projecting element 32, by which it is secured in the handle or lever 15 overlies and extends to either side of the hook 45 element 28. Ribs 38 are formed integrally with the lever 15 so as to lie in overlapping relation with the two upper lateral edges of the housing 16 when the lever is secured by the catch mechanism.

The operation of this mechanism is relatively simple. The handle or lever 15 is shown in secured position in Figure 1. By inserting the key in the cylinder lock and turning the same to the left, the pawl 27 is rotated in a counterclockwise 50

direction, as seen in Figure 3. From Figure 4 it is apparent that the nose of this pawl 27 engages the hook element 28, and accordingly this hook element is carried to the left out of engagement with the hook element 32. The lever or handle 15 is now free to be lifted. In accordance with the disclosure in my prior application above identified, the bolts are withdrawn by means of the inward travel of the linkages 7 and 8 when the lever 15 is lifted or swung in a clockwise direction, as viewed in Figure 1.

When the operator wishes to shut the closure of a refrigerator car or the like, he swings the lever or handle 15 downwardly to the position shown in full lines in Figure 3. The portion of the handle 15 to which the hook element 32 is secured is pushed down behind the guard 34, and this hook element first deflects the hook element 28 and then the latter snaps into place to secure the handle in this position until the lock cylinder is again rotated.

This construction is to such a high degree resistant to tampering that it is almost impossible to pick the lock. Any flat blade or other instrument used for picking the lock would have to make two right-angle bends before it could get into contact with the hook element 28 or latch 27. The hook element 32 is rigid, and therefore, the tool used in an attempt to pick the lock would have to turn downwardly, no matter whether the tool were inserted from the right or left (as viewed in Figure 3). If inserted from the right, the tool would have to follow down along the straight right side of the hook element 32, and then make a second right-angle bend to get around the lower end of the element 32 into contact with the pawl or hook element 28. I know of no instrument that is flexible enough to make these bends and still be strong enough to push the hook element 28 out of locking position against the spring 29.

If the tool were inserted from the left hand side, it would have to make one right-angle bend downwardly and would then have to make a

reverse bend along the deep shoulder 36 before coming in contact with the hook element 28. It will be apparent that this construction in which the hook element 28 is contained well within its housing 16 and cooperates with a projecting portion of the lever or handle 15 has decided advantages, so far as security is concerned.

This construction has the further advantage that it is not necessary for the body builder to maintain so high a degree of accuracy in mounting the housing 16 with relation to the path of travel of the handle or lever 15. Even though the ribs 38 do not nicely fit the two upper edges of the housing 16, the construction practically avoids the possibility of picking of the lock, and therefore, there is a larger tolerance as to the fit.

While I have illustrated and described the embodiment of my invention which I at present prefer, it will be understood that the invention may be otherwise embodied and practiced within the scope of the following claim.

I claim:

Catch mechanism for truck door locks comprising an operating lever mounted for movement in a plane parallel with the door having a depending hook element thereon, a casing mounted on the door having a pivoted hook-like keeper therein, said casing having an opening in the top thereof through which the hook-like member on the operating handle may pass, a spring for resiliently urging the hook-like keeper into position to engage the hook-like member on the handle, the hook-like member and the hook-like keeper having inclined ratchet faces to enable the hook-like member on the handle to cam the hook-like keeper against the resistance of the spring to one side when the hook-like member is being projected into the casing, the spring serving to return the keeper to locking position after the hook-like projection on the handle has entered the casing to its full limit, and a key lock including a lock barrel pivotally supported in the casing for releasably holding the keeper in locked position.

CARL R. HENNICK.
